UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

ELECTRICAL APPARATUS FOR INTERNAL-COMBUSTION ENGINES.

1,362,770.

Specification of Letters Patent. Patented Dec. 21, 1920.

Application filed November 24, 1915. Serial No. 63,195.

To all whom it may concern:

Be it known that I, JOSEPH BIJUR, a citizen of the United States, and a resident of the borough of Manhattan, city, county, and State of New York, have invented an Improvement in Electrical Apparatus for Internal-Combustion Engines, of which the following is a specification.

This invention relates to electrical apparatus for internal combustion engines. One of the objects thereof is to provide apparatus of the above type of simple construction in which the parts are compactly disposed and securely held in position. Another object is to provide apparatus of the above type in which the parts may be readily and conveniently assembled in exact position for most effective action. Another object is to provide for starting motors a practical and inexpensive mounting of few parts and efficient action. Other objects will be in part obvious and in part pointed out hereinafter.

The invention accordingly consists in the features of construction, combinations of elements and arrangement of parts which will be exemplified in the structure herein-after described and the scope of the application of which will be indicated in the following claims.

In the accompanying drawings in which is shown one of various possible embodiments of this invention,

Figure 1 is a diagrammatic side elevation, certain parts being cut away in order to show the construction more clearly.

Fig. 2 is a detail end view of a portion of the parts shown in Fig. 1.

Fig. 3 is a sectional elevation taken substantially on the line A—A of Fig. 2.

Similar reference characters refer to similar parts throughout the several views of the drawings.

Referring now to Fig. 1 of the drawings, there is shown at 1 an internal combustion engine comprising a fly wheel 2, and it may be noted that this engine is preferably of the automobile type. Preferably formed integral with the engine casing 3 is a casing 4 extending about the fly wheel and provided with the flange 5 by which it may be connected with a similar casing to inclose the parts, the latter casing not being here shown as it forms in itself no part of the present invention.

The fly wheel 2 is provided with a spur gear 6 normally out of mesh with a pinion 7 on the squared armature shaft 8 of an electric motor 9. Although this dynamo is here shown as a motor, it is to be understood that many of the features of this invention are applicable to the mounting of a dynamo of the generator form.

The pinion 7 is provided with a grooved collar 10 in which fits a fork 11 upon the shifting rod 12 which is connected by the pivoted link 13 with the lower end of a bell crank lever 14. This lever is forked about the link rod 13 between a fixed collar 15 and a yielding collar 16 held in position by the spring 17 and nut 18. Lever 14 is provided with a fixed pivot 19 from which it extends upwardly to the foot pedal 20 by which it is actuated from the seat of the motor car, and it is normally retracted into the position shown by the spring 21 connected between its lower end and a fixed part of the vehicle 22. Connected to the lever 14 at the pivot 23 is an actuating rod 24 of a switch box 25. This rod bears the suitably insulated contact 26 adapted when moved in the direction indicated by the arrow to bridge the contacts 27 and complete the circuit of the motor 9 from any suitable source of current, the electrical connections not being here shown as they form in themselves no part of the present invention. It is to be understood accordingly that as the foot pedal 20 is depressed, its lower end, by the connections above described, carries the pinion 7 toward and into mesh with the gear 6 of the fly wheel, at the same time completing the motor circuit, thus causing the pinion to rotate and turn over the engine to start the latter.

The motor 9, as best shown in Fig. 3 of the drawings, comprises an outer shell or casing 28 which fits within the annular flange or socket 29 upon a supporting member 30 and is retained in position therein partially by means of the longitudinal screws 31 and partially by the radial screws 32. Screws 31 pass through the body of the member 30 and screws 32 through its flange 29. It will be seen from this construction that the member 30 not only acts as a support for the motor, but also as one of the heads of the motor casing having therein the bearing 33 for the motor shaft 8 upon which the pinion 7 is mounted to slide. The

member 30 is provided with the outwardly extending wings 34, as best shown in Fig. 2 of the drawings, and each of these is provided with an opening through which a 5 bolt 35 secures it to the casing 4, these bolts being three in number.

There is formed in the casing 4 a circular opening 40 precisely concentric to the desired position of the motor shaft of larger 10 diameter than the pinion 7 and upon the surface of the fitting 30 toward the fly wheel there is a projecting boss 36 accurately turned concentric with the axis of the motor shaft and adapted to fit closely the opening 15 in the casing 4 except at the points where the registering recesses 37 permit access to the screws 31.

By this arrangement, the member 30 is interlocked with the casing in precisely the 20 desired position for proper and efficient meshing between the pinion 7 and the gear 6, and the outwardly extending wings 34 together with the socket 29 provide so rigid and secure a mounting for the motor that 25 additional support is unnecessary and the end thereof away from the fly wheel may be left free.

In the use of the above apparatus, the parts are assembled by first securing the 30 fitting 30 about the end of the motor as by the screws 31 and 32, and the pinion 7 is mounted upon the extended shaft 8. The opening in the casing being exactly the same in position and size for a given type of motor is positioned to receive the boss 36 without fitting or adjustment, the extended shaft and the pinion 7 readily passing through the opening 40, and the bolts or heavy screws 35 are thereupon driven into position. The actuating linkage then being 40 connected, the parts are in condition for use by the manipulation of the foot pedal hereinbefore described. The pinion is thrown into mesh with the fly wheel to turn 45 over and start the engine or is thrown out of mesh upon the release of the pedal as the parts are drawn back by the spring 21.

It is to be understood that the linkage is merely illustratively shown and that other 50 means may be employed for power transmission. The specific form of linkage shown is fully described and claimed in the co-pending application of Lionel M. Wolffsohn, Serial No. 153,359 filed March 8th, 55 1917. The invention herein claimed is substantially independent of the manner and means for transmitting power between the dynamo and the engine.

It will thus be seen that there is provided 60 simple and compact and yet thoroughly effective and reliable apparatus in which the several objects of this invention are achieved.

As various possible embodiments might 65 be made of the above invention and as va-

rious changes might be made in the embodiment above set forth, it is to be understood that all matter herein set forth or shown in the accompanying drawings is to be interpreted as illustrative and not in a limit- 70 ing sense.

I claim as my invention:

1. In combination, an engine, a dynamo having supporting means near one end with a portion at right angles to the axis of 75 said dynamo, facing and secured to a vertical part of said engine, said dynamo extending from said means in a horizontal direction, a first power transmitting member for said engine, and a second power transmitting member for said dynamo mounted on the shaft thereof and disposed laterally 80 of said first member and in the plane thereof when in operative position relative thereto.

2. The combination in an engine in which the flywheel is provided with peripheral gear teeth for application of starting torque, of a starting motor unit having a casing element, outstanding supporting 90 means attached to said element having a portion disposed in a plane at right angles to the axis of said motor unit, facing and secured to a vertical portion of the engine casing, said unit including a shaft element 95 encircled by said casing element, said shaft carrying a pinion adapted to mesh with the teeth on said flywheel.

3. The combination in an engine of the type provided with a toothed wheel and a 100 vertical casing element adjacent to and parallel to the surface of said wheel, of a dynamo unit having an inclosure, said unit including a positioning member telescoped with respect to said inclosure and secured 105 to said casing element, an extended shaft for said dynamo passing through said positioning member, and a second toothed wheel mounted on said shaft and arranged laterally of said first toothed wheel and in 110 the plane thereof for power transmission.

4. The combination in an engine of the type provided with a toothed wheel and a 115 vertical casing element adjacent to and parallel to the surface of said wheel, of a dynamo having an end head provided with a supporting flange resting against said casing element and secured thereto, said dynamo having an extended shaft, and a second toothed wheel on said shaft laterally 120 and in the plane of said first wheel for power transmission.

5. The combination in an engine of the type provided with a toothed wheel and a vertical casing element adjacent to and parallel to the surface of said wheel, of a dynamo unit including an inclosure, a supporting plate secured thereto, a projection extending from said unit into a hole in said casing element, said plate closing said hole 130

and having outstanding wings by which it may be bolted to said casing element, an extended shaft for said dynamo, said projection aiding to support said shaft, and a second toothed wheel mounted on said shaft and arranged laterally and in the plane of said first wheel for power transmission.

6. In combination, an engine including a toothed wheel and having a casing provided 10 with a flat surface portion, of a dynamo unit including an inclosure, a support member secured to said inclosure and having a pilot fitting into a corresponding hole in said flat surface, said support member having a 15 flange contacting said flat surface about said hole, bolts for securing said flange to said flat surface, an extended shaft for said dynamo, and a second toothed wheel mounted on said shaft and arranged laterally and in 20 the plane of said first wheel for power transmission.

7. In electrical apparatus for internal combustion engines, in combination, an engine provided with a flywheel, a casing 25 about said flywheel having a flat surface parallel to said flywheel, a motor mounted near one end upon said flat surface, said motor extending freely from said casing in a horizontal direction, gear teeth upon said 30 flywheel, and a pinion upon the shaft of said motor adapted to mesh with said flywheel and of smaller diameter than said hole, whereby said motor with said pinion in place thereon may readily be assembled 35 as a unit upon said engine casing.

8. The combination in an engine in which the flywheel is provided with peripheral gear teeth for application of starting torque and in which a vertical portion of the engine 40 casing is adjacent to and parallel to said flywheel, of a starting motor unit having a yoke and an end head telescoped with respect to the end of said yoke, means securing said end head to said casing portion for 45 supporting said unit, an extended shaft for said motor having a bearing in said head, and a pinion mounted on said shaft adapted to mesh with said gear teeth.

9. The combination in an engine of the type provided with a driven gear and a vertical casing element adjacent to and parallel to the surface of said gear, of a dynamo unit including an inclosure, a support member secured thereto, said member comprising a pilot having a portion extending therefrom and telescoped with respect to said inclosure, a pilot extending therefrom in the opposite direction and fitting into a corresponding hole in said casing element, and means securing said support member to said casing element for supporting said dynamo unit, said unit including a transmission element for meshing with said driven gear.

10. In combination, an engine having a casing, a dynamo having a yoke and an end- 65 plate, said plate having a pilot on one face telescoped with respect to said yoke, a pilot on the opposite face fitting into a corresponding opening in a vertical portion of said casing, said plate having outstanding 70 portions resting against said casing portion and bolted thereto, whereby said dynamo may extend freely from said engine in a horizontal direction, a shaft for said dynamo having a bearing lodged in said plate, 75 a toothed member on said shaft on the side of said engine casing opposite said dynamo, a second toothed member on said engine, said toothed members being arranged laterally of each other and in the same plane 80 for power transmission.

11. In combination, an engine, a dynamo unit having a supporting plate provided with an outstanding portion secured to a part of said engine, said plate carrying a bearing for the shaft of said dynamo, a transmission wheel mounted on the shaft of said dynamo, a second transmission wheel for said engine, said wheels being disposed laterally of each other for power transmission in a single plane parallel to that of said supporting plate.

In testimony whereof, I have signed my name to this specification this fifteenth day of November, 1915.

JOSEPH BIJUR.
